(57) **CLAIM**

The ornamental design for a suspension housing for camera mount, as shown and described.

DESCRIPTION

FIG. 1 is a top, front, right side perspective view of a suspension housing for camera mount, showing our new design in condition of use;

FIG. 2 is a top, front, right side perspective view;

FIG. 3 is a top, rear, right side perspective view, shown in condition of use;

FIG. 4 is a top, rear, right side perspective view;

FIG. 5 is a front elevation view, shown in condition of use;

FIG. 6 is a front elevation view;

FIG. 7 is a rear elevation view, shown in condition of use;

FIG. 8 is a rear elevation view;

FIG. 9 is a right side elevation view, shown in condition of use;

FIG. 10 is a left side elevation view thereof;

FIG. 11 is a top plan view thereof; and,

FIG. 12 is a bottom plan view thereof.

The broken lines showing for horizontal tabs, most clearly shown in FIG. 2, represent portions of the article that form no part of the claimed design.

The dash-dot-dash lines in the drawings represent boundaries of the design and from no part of the claimed design.

All other broken lines in the drawings depict environmental subject matter only and form no part of the claimed design.

1 Claim, 11 Drawing Sheets
